(57) **CLAIM**

The ornamental design for a bladeless hand held fan, as shown and described.

DESCRIPTION

FIG. 1 is a perspective view showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depicting various structural elements in the figures are included for the purpose of illustrating portions of the article that form no part of the claimed design.

1 Claim, 4 Drawing Sheets
